UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

BLINDSTITCH SEWING-MACHINE.

1,276,217.

Specification of Letters Patent. Patented Aug. 20, 1918.

Application filed May 27, 1916. Serial No. 100,320.

To all whom it may concern:

Be it known that I, THOMAS J. HAYES, a citizen of the United States, and resident of Roslindale, county of Suffolk, State of 5 Massachusetts, have invented an Improvement in Blindstitch Sewing-Machines, of which the following description, in connection with the accompanying drawing, is a specification, like characters on the drawing 10 representing like parts.

This invention relates to improvements in sewing machines of the "Arbette" type which are adapted for use in felling a superimposed layer upon a base layer of material.

The principal object of the invention is to improve the stitch forming mechanism proper to adapt the machine to form stitches in the base and superimposed layer with a 20 relatively small amount of lateral vibration or shogging of the needle and to form a seam in which the points of penetration and emergence of the needle will lie well back from the folded edge of the superimposed 25 layer so that the seam will be wholly or substantially concealed.

This is accomplished in the preferred embodiments of the invention disclosed herein by a sewing machine comprising a needle 30 and complementary stitch forming mechanism located above the work support provided with means for advancing the needle in its penetrating stroke in the general direction of the line of feed of the material across 35 the work support and with means for positioning the needle to cause it in one series of stitches to enter the superimposed layer substantially in parallelism to the edge of said layer and in another series of stitches 40 to enter the base layer adjacent the edge of the superimposed layer in a direction diverging from said layer, suitable means, preferably a bobbin thread concatenating the loops of the thread in the rows of stitches, serving 45 to bind the superimposed layer firmly upon the base layer.

The drawings illustrate the invention as embodied in blind stitch sewing machines of the "Arbette" type.

50 In the drawings;

Figure 1 is a front view of a sewing machine having a curved needle oscillating in a plane inclined to the vertical plane of the line of feed, a portion of the arm being

broken away to show the means for vibrating the needle laterally, 55

Fig. 2 is an end view of the machine with the face plate removed and certain parts omitted to show more clearly the mechanism for vibrating the needle laterally, the 60 feeding and bender mechanism being omitted,

Fig. 3 is a plan view of the presser foot resting upon the work and showing the position of the needle when forming a stitch in 65 the superimposed layer,

Fig. 4 is a similar view showing the position of the needle when making a stitch in the base layer,

Fig. 5 is a front elevation of the head of 70 a different form of machine with the face plate removed and a portion of the head broken away to display the needle actuating mechanism and also showing the presser foot and work support, 75

Fig. 6 is a plan view of the presser foot illustrated in Fig. 5 resting upon the work and showing the position of the needle in making a stitch in the superimposed layer, 80 and,

Fig. 7 is a similar view showing the position of the needle when engaging the base layer.

For the purposes of this disclosure it is unnecessary to illustrate or describe the 85 feeding mechanism or the bender mechanism or the means for actuating the same as the essence of the invention resides in the needle actuating mechanism and the parts which present the work, particularly the superimposed layer, to the needle. 90

The machine illustrated in Figs. 1 to 4 of the drawing comprises the bed plate 1 having a hollow standard 2 and overhanging arm 3 terminating in a head 4 which contains or supports the needle mechanism and complementary stitch forming mechanism and the means for actuating them, which are operated by the usual main shaft 5 which extends axially through the arm and is provided with the usual pulley 6 and hand wheel 7.

The needle 8, which preferably is curved, is carried at one end of a needle bar 9 having a hub 10 which is mounted upon an inclined shaft 11 which is mounted in arms 12, 13 of a bracket 14 depending from a vertical rock shaft 15 which is rotatably mounted in a

suitable bearing 16 in the head 4 of the machine. The upper end of the rock shaft 15 is provided with an arm 17 which is connected by a universal joint with the end of 5 an actuating lever 18.

The needle bar 9 is preferably extended beyond the hub and connected at its end by a universal joint 20 to the end of a link 21 which may be reciprocated by a crank disk 10 or any other suitable mechanism (not shown) connected with the main shaft 5.

In the preferred embodiment of the invention illustrated in Figs. 1 and 2, the needle is oscillated in a plane inclined to the 15 vertical plane of the line of feed and the axis of the vertical rock shaft 15 lies in the same vertical plane as the axis of the oscillating needle so that the penetrating thrust of the needle is always radial to a center C, (Figs. 3 and 4,) located a short distance in advance of the points at which the needle is thrust into the base and superimposed layers.

Inasmuch as the axis of vibration of the 25 needle is located closely adjacent to the path of the edge of the superimposed layer and because by turning up its edge the superimposed layer is further separated from the base layer by the guide as the work is fed 30 forward for the next step in the base layer, as will be more fully described hereinafter, only a small amount of lateral vibration of the needle is required to cause it in one series of strokes to penetrate the superimposed layer and in another series of strokes to avoid the edge of said layer and penetrate only the base layer which is presented to it by the usual bender 22.

Any suitable means may be provided for 40 oscillating the rock shaft 15. A preferred mechanism is illustrated in Fig. 1 by means of which the amplitude of vibration of the needle may be accurately adjusted. In this mechanism the lever 18 is formed in two 45 parts 18, 18^a preferably joined together by bolt and slot connections 23 to permit the length of the lever to be adjusted properly in assembling the machine. The portion 18^a of the lever is bifurcated at its end to form 50 a cam fork 24 which engages a cam 25 upon a vertical countershaft 26 which is journaled in suitable bearings in the standard, one of which, 27, is shown. The countershaft 26 is provided at its upper end with a beveled 55 gear 28 which meshes with a beveled gear 29 on the main shaft 5, the ratio of the gears being two to one so that the needle preferably is vibrated laterally upon alternate thrusts to penetrate respectively the 60 superimposed and base layers.

The lever portion 18^a is provided with a stud 30 by which it is pivotally connected to the end of a link 31 which is pivotally connected to a stud 32 at the end of an arm 33 65 of a bell crank lever 34 which is pivoted

upon a convenient stationary part of the machine, shown herein as one of the bosses 35 in which the main shaft 5 is journaled. The other arm 36 of the bell crank lever is provided with a reduced extension 37 which 70 passes through a slot (not shown) in the arm 3 and is suitably secured in adjusted position by a nut on said extension 37 engaging the wall of the arm.

By reason of the above construction the 75 stud 32 may be positioned either in the vertical axial plane of the lever 18—18^a or to one side thereof so that the resultant longitudinal movement of the lever caused by the arcuate movement of the stud 30 may be adjusted with great accuracy by the adjustment of the bell crank lever 34, and the amplitude of vibration of the needle fixed with greatest precision. This is very desirable especially when a thin fabric is to be 85 blind stitched upon a base layer.

Any suitable complementary stitch forming mechanism may be utilized to concatenate the loops of needle thread. A desirable mechanism which is illustrated herein comprises a rotating bobbin carrying hook 38 secured to the lower end of a shaft 39 which is journaled in a hook bracket 40 depending from, and preferably integral with, the head 4. The shaft 39 is provided at its upper end with a beveled gear 41 which meshes with a beveled gear 42 upon the main shaft, the gears 41, 42 being of such relative diameters to give the desired speed of rotation to the hook to coöperate properly with the needle 95 in both of its paths of oscillation.

The work may be presented to the needle in any suitable manner but preferably is supported at and adjacent to the stitching point by a work support 43 having a work supporting surface 44 inclined to the vertical plane of the line of feed at a greater angle than that of the inclination of the plane in which the needle oscillates. By this construction the needle is enabled to 105 pass beneath a greater number of the surface threads of the base layer without penetrating deeply, than if the work supporting surface of the work support were horizontal.

The inclination of the face of the work support also facilitates the entry of the needle well beneath the superimposed layer, particularly when combined with special guiding means for the superimposed layer which is adapted to roll up the edge of said layer. The preferred form of guide for the edge of the superimposed layer is illustrated herein as embodied in the presser foot 45 which preferably is secured to an extension 46 of the hook bracket 40.

The presser foot comprises a major toe portion 47 and a minor toe portion 48, the major toe portion preferably having a concaved upper face 49 a portion of which is adapted to support and guide the oscillating 130

needle, an aperture 50 being provided adjacent its base to permit the base layer to be thrust into the path of the needle by the bender 22. The under surface 51 of the 5 minor toe portion preferably is convexedly curved and thereby adapted by its engagement with the upper surface of the superimposed layer to crowd the edge of the layer toward the path of the needle.

10 A special guide for the edge of the superimposed layer is provided which is adapted to surround or embrace the edge of said layer in advance of and closely adjacent to the stitching point. This guide may be supported in any convenient manner but preferably is in the form of a plate 52 attached by screws 53 to the top of the minor toe portion 48 of the presser foot and extends beyond the path of the needle 8. The under 15 surface of the guide preferably is conoidal in form and serves to roll up the edge of the superimposed layer so that the needle may enter, in one series of its penetrating strokes, the under surface of said layer well back 20 from the edge thereof and emerge from said layer beneath and beyond said edge so that the stitch in said layer will be fully concealed. The free end of the edge guide preferably extends downwardly to rest upon 25 the surface 49 of the major toe portion 47 of the presser foot and thereby prevents the superimposed layer from improperly reaching the path of the needle.

30 In the operation of the machine the needle vibrating mechanism is positioned to cause the needle in one series of penetrating strokes to oscillate in a plane substantially parallel to the edge of the superimposed layer so that it will enter and emerge from the under face of said layer at points nearly 35 equidistant from the edge thereof. In making the other series of penetrating strokes the needle is vibrated laterally about the axis C so that it advances in its penetrating 40 stroke in a path diverging from the superimposed layer, thus avoiding the edge of the superimposed layer and penetrating the surface of the base layer which in the meantime has been elevated into its path by the 45 bender 22.

50 By the construction above described a blind stitch seam may be made in which the edge of the superimposed layer overlies the lines of stitching a considerable distance, 55 thus enabling such seams to be made as those which fasten the linings to the bottoms of coats. It is however, to be understood that my invention is not limited to a mechanism for vibrating the needle in a 60 plane inclined to the vertical plane of the line of feed and that other mechanisms may be utilized for actuating the needle.

65 Another preferred embodiment of the invention is illustrated in Figs. 5, 6, and 7 in which Fig. 5 shows the end 60 of a sewing

machine arm having a head 61 supporting suitable mechanism for actuating a needle which is oscillated in vertical planes which are perpendicular to the work supporting surface of a preferably horizontal work 70 support 62. In this embodiment the mechanism is, in the main, similar to that disclosed in Patent No. 937,273, granted Oct. 19, 1909, to Wolf Arbetter but differs from the construction shown therein in that the 75 path of the needle in its penetrating stroke enters the superimposed layer in parallelism with the direction of feed, and with the edge of said layer, instead of penetrating said layer at an angle to its edge; and in 80 that the needle penetrates the base layer in a direction diverging from said layer instead of in a direction parallel to the direction of feed.

85 It also differs from the construction disclosed in that patent in that special guiding means are provided for the edge of the superimposed layer which present said layer to the needle in one series of its penetrating strokes so that a more perfect blind 90 stitch may be made.

95 Any suitable work support, feeding and bender mechanism such for example as that disclosed in the Arbetter Patent No. 830,699 may be employed in combination with the 95 mechanism shown in Figs. 5, 6, and 7, therefore no detail illustration or description of them is necessary.

100 The mechanism illustrated herein comprises a main driving shaft 63 extending horizontally through the head 61 and provided at its forward end with a pinion 64 adjustably connected thereto by set screws 65. On the face of the pinion 64 a rotarily adjustable crank disk 66 is mounted, the 105 crank pin 67 being connected to the needle oscillating rod 68.

110 A grooved cam 69 mounted upon a stub-shaft 70 and driven by a gear 71 meshing with the gear 64 serves to vibrate the needle laterally through the following mechanism. A vertical shaft 72 is mounted in the lower portion of the head and carries at its lower end a long transverse bearing 73 the axis of which is at right angles to, and lies in the 115 same vertical plane as, the axis of the rock shaft 72. The needle carrying rock shaft 74 mounted in this bearing is provided at one end with an arm, or needle bar 75 which holds at its end a curved needle 76 and at its 120 opposite end is provided with an arm 77 which is connected by a universal joint 78 to the end of the needle actuating link 68 above described.

125 The rock shaft 72 is provided at its upper end with a slotted arm 79 which is attached adjustably to it by a set screw 80.

At the rear of the head a short vertical shaft 81 is mounted in a suitable bearing in the head and is provided at its lower end 130

with an arm 82, the arm 82 having an upwardly extending stud which engages the cam groove 69, whereby said arm is vibrated. The arm 82 also has a T-shaped slot 83 in which is mounted a sliding carrier 84 having a downwardly extending stud 85 which enters a slot in the arm 79. The carrier 84 is adjustably movable longitudinally of the T-shaped slot 83 by an adjusting screw 86 having a knurled head. By adjusting the carrier toward and from the shaft 81 the amplitude of vibration of the needle may be varied as desired.

Any suitable complementary stitch forming mechanism may be used with the needle mechanism above described, preferably however it is in the form of a revolving hook suitably supported upon a bracket (not shown) connected with the head of the machine.

It will be noted that the axis of the shaft 74 is shown at a considerable distance in the rear of the axis of the vertical rock shaft 72. This construction provides for the securing of the requisite penetration of the needle in making the diagonal stitch with a minimum amount of divergence of the needle from the plane which is parallel to the line of feed.

By thus placing the axis of the shaft 74 in the rear of the axle of the vertical rock shaft 72 the needle is swung bodily about the vertical axis of the shaft 72 in a circle whose radius is that of the distance between the axis of the shafts 74 and 72 so that the needle penetrates the base and superimposed layers in points at once closely adjacent to each other and a short distance in the rear of the axial line of the shaft 72 and a minimum amount of divergence from the path of the needle is provided which enables the needle properly to coöperate with the revolving hook in both its straight and diagonal paths.

The screw 86 and connected parts above described enables an adjustment to be made between the straight stitch, which is in the direction of the line of feed and the diagonal stitch which diverges away from the superimposed layer for different kinds of work without disturbing the position of the needle in making the straight stitch which it is desired to maintain.

In assembling the machine the shaft 72 is adjusted rotarily in respect to the arm 79 so that the needle will, upon its penetrating movement in a superimposed layer, oscillate in a plane parallel to said layer. The set screw 80 is then set up to maintain the parts permanently in this position. The screw 86 is then operated to shift the position of the stud 85 and consequently the throw of the arm 79 so to position the needle as to make a stitch in the base layer diverging away from the straight stitch and from

the edge of the superimposed layer to the desired amount.

In order properly to present the superimposed layer to the needle so that the needle upon the straight stitch, which is in parallelism with the line of feed, may enter and emerge properly from said layer, a special form of guide is provided of the general character described in connection with the mechanism illustrated in Figs. 1 and 2. This guide in the preferred embodiment of the invention shown in Figs. 5, 6, and 7, forms a part of the presser foot 87 which has an arm 88 extending upwardly and adjustably secured by screw and slot connections to a post 89 extending downwardly from the head 61. The presser foot comprises a major toe portion 90 and a minor toe portion 91, the major toe portion being formed with a recess 92 to provide a throat through which the layer may be thrust into the path of the needle upon its diverging stroke. The major toe portion 90 may also be suitably formed to support and guide the curved oscillating needle. The minor toe portion 91 is provided with a convexedly curved under surface 93 which is adapted to crowd the material of the superimposed layer toward the path of the needle. A guide 94 of the character above described is secured to the top of the presser foot and has a curved guiding extension projecting over and beyond the path of the needle in its straight stitch, said guide embracing the edge of the superimposed layer in front of and adjacent to the stitching point and causing the layer to be rolled up so that the needle on its straight thrust will enter beneath the edges of said layer.

In the operation of the machine the needle is reciprocated in paths which respectively are substantially parallel to the direction of the line of feed and diverging from said line of feed and from the superimposed layer.

The superimposed layer is directed by the guide in the path of the needle upon its straight stitch so that it enters the superimposed layer under the edge thereof and emerges from said layer beneath or at the edge. Upon its withdrawal from the superimposed layer the needle is oscillated by the mechanism above described so that its point is directed away from the superimposed layer and upon the next succeeding thrust the needle penetrates the base layer, which in the meantime has been raised into its path by the bender, the revolving hook, or other complementary stitch forming mechanism serves to concatenate the loops of needle thread in both series of stitches so that when the stitches are set by the tension the edge of the superimposed layer is drawn down upon the base layer and the line of stitching wholly or substantially concealed.

It will be understood that the embodiments of the invention disclosed herein are illustrative and not restrictive and that various other means may be utilized for performing the results attained by this invention within the meaning and scope of the following claims.

Having thus described my invention what I claim as new and desire to secure by Letters Patent is:

- 10 1. A blind stitch sewing machine for felling a superimposed layer upon a base layer of material comprising a work support, means for feeding the material over the work support, a needle and complemental stitch forming mechanism located above said work support, means for advancing the needle in its penetrating strokes in the general direction of feed and means for positioning the needle to cause it in one series of strokes to enter the superimposed layer substantially in parallelism with the edge thereof, and in another series of strokes to enter the base layer adjacent the edge of the superimposed layer in a direction diverging away from the edge of said layer. 70
- 15 2. A blind stitch sewing machine for felling a superimposed layer upon a base layer of material comprising a work support, means for feeding the material over the work support, a needle mounted to oscillate in a plane inclined to the work supporting surface of the work support and complemental stitch forming mechanism located above said work support, means for oscillating the needle in its penetrating strokes in the general direction of feed and means for positioning the needle to cause it in one series of strokes to enter the superimposed layer substantially in parallelism with the edge thereof and in another series of strokes to enter the base layer adjacent the edge of the superimposed layer in a direction diverging away from the edge of said layer. 75
- 20 3. A blind stitch sewing machine for felling a superimposed layer upon a base layer of material comprising a work support, means for feeding the material over the work support, a needle and complemental stitch forming mechanism located above said work support, means for advancing the needle in its penetrating strokes in the general direction of feed, means for swinging the needle about a fixed vertical axis to cause it in one series of strokes to enter the superimposed layer in front of said axial position substantially in parallelism with the edge thereof and in another series of strokes to enter the base layer also in front of said axial position in a direction diverging away from the edge of said layer. 80
- 25 4. A blind stitch sewing machine for felling a superimposed layer upon a base layer of material comprising a work support, means for feeding the material over the work support, a needle and complemental stitch forming mechanism located above said work support, means for advancing the needle in its penetrating strokes in the general direction of feed and means for positioning the needle to cause it in one series of strokes to enter the superimposed layer substantially in parallelism with the edge thereof, and in another series of strokes to enter the base layer adjacent the edge of the superimposed layer in a direction diverging from said layer. 85
- 30 5. A sewing machine for blind stitching comprising a work support, a curved oscillating needle and complemental stitch forming mechanism located above the work support, means for oscillating said needle laterally and means for vibrating the needle to cause its oscillations to occur in diverging paths, the axis of said oscillating movement and the axis about which the needle is vibrating laterally being located in the same vertical plane whereby all penetrating thrusts of the needle are radial to a center located in the line of the axis about which the needle is vibrated. 90
- 35 6. A sewing machine for blind stitching a superimposed layer upon a base layer of material comprising a work support and means for feeding the material over said work support, a vertical rock shaft, a needle shaft supported by and transversely of said rock shaft, means for oscillating said needle shaft, means for vibrating said rock shaft including a longitudinally movable floating lever pivotally connected to said vertical rock shaft, and a cam for actuating said lever to cause the needle to oscillate in different diverging planes. 95
- 40 7. A sewing machine for blind stitching a superimposed layer upon a base layer of material comprising a work support and means for feeding the material over said work support, a vertical rock shaft, a needle shaft supported by and transversely of said rock shaft, means for oscillating said needle shaft, means for vibrating said rock shaft including a longitudinally movable floating lever pivotally connected to said vertical rock shaft, a cam for actuating said lever to cause the needle to oscillate in different diverging planes and means for varying the position of the fulcrum of said lever transversely of the axis of said lever whereby the extent of longitudinal movement of said lever and the consequent amplitude of vibration of the rock shaft may be adjusted with precision. 100
- 45 8. A blind stitch sewing machine for felling a superimposed layer upon a base layer of material comprising a bed plate, a work 105
- 50 9. A blind stitch sewing machine for felling a superimposed layer upon a base layer of material comprising a work support, means for feeding the material over the work support, a vertical rock shaft, a needle shaft supported by and transversely of said rock shaft, means for oscillating said needle shaft, means for vibrating said rock shaft including a longitudinally movable floating lever pivotally connected to said vertical rock shaft, a cam for actuating said lever to cause the needle to oscillate in different diverging planes and means for varying the position of the fulcrum of said lever transversely of the axis of said lever whereby the extent of longitudinal movement of said lever and the consequent amplitude of vibration of the rock shaft may be adjusted with precision. 110
- 55 10. A blind stitch sewing machine for felling a superimposed layer upon a base layer of material comprising a work support, means for feeding the material over the work support, a vertical rock shaft, a needle shaft supported by and transversely of said rock shaft, means for oscillating said needle shaft, means for vibrating said rock shaft including a longitudinally movable floating lever pivotally connected to said vertical rock shaft, a cam for actuating said lever to cause the needle to oscillate in different diverging planes and means for varying the position of the fulcrum of said lever transversely of the axis of said lever whereby the extent of longitudinal movement of said lever and the consequent amplitude of vibration of the rock shaft may be adjusted with precision. 115
- 60 11. A blind stitch sewing machine for felling a superimposed layer upon a base layer of material comprising a work support, means for feeding the material over the work support, a vertical rock shaft, a needle shaft supported by and transversely of said rock shaft, means for oscillating said needle shaft, means for vibrating said rock shaft including a longitudinally movable floating lever pivotally connected to said vertical rock shaft, a cam for actuating said lever to cause the needle to oscillate in different diverging planes and means for varying the position of the fulcrum of said lever transversely of the axis of said lever whereby the extent of longitudinal movement of said lever and the consequent amplitude of vibration of the rock shaft may be adjusted with precision. 120
- 65 12. A blind stitch sewing machine for felling a superimposed layer upon a base layer of material comprising a work support, means for feeding the material over the work support, a vertical rock shaft, a needle shaft supported by and transversely of said rock shaft, means for oscillating said needle shaft, means for vibrating said rock shaft including a longitudinally movable floating lever pivotally connected to said vertical rock shaft, a cam for actuating said lever to cause the needle to oscillate in different diverging planes and means for varying the position of the fulcrum of said lever transversely of the axis of said lever whereby the extent of longitudinal movement of said lever and the consequent amplitude of vibration of the rock shaft may be adjusted with precision. 125

support having its work supporting face inclined to the plane of the bed plate, means for feeding the material over the work support, a curved needle and a complementary 5 stitch forming mechanism located above the work support, means for oscillating said needle in a plane inclined to the work supporting surface of the work support and to the vertical plane of the line of feed and 10 means for positioning the needle to cause it in its penetrating movement in one series

of strokes to enter the under surface of the superimposed layer beneath and in a direction substantially in parallelism with the edge thereof and in another series of stitches 15 to enter the base layer adjacent the edge of the superimposed layer in a direction diverging from said layer.

In testimony whereof, I have signed my name to this specification.

THOMAS J. HAYES.
